CLAIM

I claim, the ornamental design for a water container, as shown and described.

DESCRIPTION

FIG. 1 is a perspective view of a water container showing our new design;

FIG. 2 is a front view of the embodiment shown in FIG. 1; FIG. 3 is a back view of the embodiment shown in FIG. 1; FIG. 4 is a top plan view of the embodiment shown in FIG. 1;

FIG. 5 is a bottom plan view of the embodiment shown in FIG. 1;

FIG. 6 is a side view of the embodiment shown in FIG. 1; FIG. 7 is another side view of the embodiment shown in FIG. 1;

FIG. 8 is perspective view of the embodiment shown in FIG. 1 in a coffee maker environment;

FIG. 9 is a perspective view of a water container showing a second embodiment of our new design;

FIG. 10 is a front view of the embodiment shown in FIG. 9; FIG. 11 is a back view of the embodiment shown in FIG. 9; FIG. 12 is a top plan view of the embodiment shown in FIG. 9;

FIG. 13 is a bottom plan view of the embodiment shown in FIG. 9;

FIG. 14 is a side view of the embodiment shown in FIG. 9; and,

FIG. 15 is another side view of the embodiment shown in FIG. 9.

The broken lines are for environmental purpose only and form no part of the claimed design.
